UNITED STATES PATENT OFFICE

ELMER KNUTSEN, OF BELLINGHAM, WASHINGTON

LAUNDRY DRIER

Application filed February 25, 1929. Serial No. 342,365.

My invention relates to improvements in laundry driers, and has for an object to provide for the movement of drier baskets in a circuit a part of which includes a closed chamber traversed by currents of heated air.

Another object of my improvement is to provide for the movement of said baskets through said chamber at a slower rate than through the remainder of said circuit.

10 Another object of my improvement is to provide for the relatively rapid axial rotation of said baskets within said chamber and the relatively slow movement thereof through the same.

15 Another object of my improvement is to provide said heated chamber with capacity for several of said baskets simultaneously.

Another object of my improvement is to provide automatic means to indicate the time 20 for discharging a basket from said chamber and placing another therein.

Another object of my improvement is to provide means to simultaneously open the doors of said drying chamber.

25 Another object of my improvement is to provide automatic means to simultaneously close the doors of said chamber.

Another object of my improvement is to provide accommodations for the easy removal 30 of the dried contents of said baskets.

Another object of my improvement is to provide for the convenient induction of said baskets into said chamber.

Other objects of my improvements will 35 appear as the description proceeds.

I attain these and other objects of my improvement with the mechanism illustrated in the two sheets of accompanying drawings forming a part of this specification in which 40 Figure 1 is a plan view of my laundry drier, Fig. 2 is a limited front elevation of the drier in section on the line 2—2 of Fig. 3, Fig. 3 is a side elevation of the drier, Fig. 4 is a sectional view of the drier on the bent line 45 4—4 of Fig. 3, Fig. 5 is an end elevation of my drier basket drawn on a larger scale and Fig. 6 is a side elevation of Fig. 5.

Similar characters refer to similar parts throughout. Certain parts are broken away 50 to show other parts hidden thereby.

With more particular reference to the designated parts: Frame sills 7, 7 have frame uprights 8, b8, c8 and d8 fastened thereto. Ramp angle bars a8, a8 are fastened between said uprights by blocks e8, e8.

55

Drying chamber 9 is a trunk of rectangular cross section with closed top, bottom and side walls, said side walls having longitudinal recesses 10, 10 therein extended outward from said trunk and the entire length of the same. Said trunk is fastened between the upper ends of frame uprights 8 and is supported thereby. To the front end of said trunk is fastened door housing and guides

11, and vertically slideable front door 12 is 60 slideable therein. Rear door 13 is fastened to transverse shaft 14 at the top and mounted in bearings fastened to said trunk for oscillation and to make a closure against flange

a13 on the rear end of the trunk. Arm 15 is 65 fastened to shaft 14 outside of one of said bearings and on its upper end is fastened counterweight 17 and eye 16. Bottom trap door 18 is fastened to shaft 19 which is mounted 70 for oscillation in bearings fastened to the trunk bottom and it is openable downward against the action of a coiled spring one end of which is shown in Fig. 3 at 20. Trap door 18 makes a closure against the lower edges

75 of the side walls of the rear of the trunk and against the bottom edge of door 13, when

closed, and extends beyond the same. Stop bar 21 is fastened to the rear pair of frame

uprights 8, 8 to limit the downward oscillations of door 18 to its position shown in 75

dotted lines at 18'. Stop bar 21 is fastened to the rear pair of frame

uprights 8, 8 to limit the downward oscillations of door 18 to its position shown in 80

dotted lines at 18'. Stop bar 21 is fastened to the rear pair of frame

uprights 8, 8 to limit the downward oscillations of door 18 to its position shown in 85

dotted lines at 18'. Stop bar 21 is fastened to the rear pair of frame

uprights 8, 8 to limit the downward oscillations of door 18 to its position shown in 90

dotted lines at 18'. Stop bar 21 is fastened to the rear pair of frame

uprights 8, 8 to limit the downward oscillations of door 18 to its position shown in 95

dotted lines at 18'. Stop bar 21 is fastened to the rear pair of frame

uprights 8, 8 to limit the downward oscillations of door 18 to its position shown in 100

dotted lines at 18'. Stop bar 21 is fastened to the rear pair of frame

25 while its lower end is pendent therefrom. Fastened to post 26 is bearing bracket 29 in which is mounted shaft 98 for revolution and on said shaft is fastened dog 30 to be engaged with and disengaged from door catch 27 by 5 oscillating shaft 98 to cause said dog to occupy its full-line position or its dotted-line position at 30'.

Rope 31 connects eye 16 of rear-door lever 10 with rope 28 below and proximate to 15 sheave 25 when both doors are closed. By pulling downward on the free end of rope 28 little longitudinal movement of rope 31 is caused till the place of its attachment to 20 rope 28 reaches the sheave when, in addition to the opening of door 12, which begun with the commencement of said movement of rope 28, door 13 begins to open and thence both front and rear doors continue to open simultaneously till the rear door has reached its 25 dotted position at 18' and the front door has reached its dotted position at 12' with its catch in its dotted position at 27' engaged by dog 30 which holds both doors in their fully-open positions, with rope 31 at 31'.

Driver pulleys 32, 32 are fastened to shaft 33 which is mounted for revolution in bearings 34, 34 fastened to said trunk to dispose 30 said pulleys across the bottom thereof protruding therethrough forward and adjacent trap door 18. On a projecting end of shaft 33 is fastened bevel gear 35 which is engaged with bevel gear 36 fastened to the lower end 35 of diagonal shaft 37. Said shaft is mounted for revolution in bearings $a37$, $b37$ fastened to said trunk. On the upper end of said shaft is fastened bevel gear 38 engaged with bevel gear 39 fastened to the end of shaft 40 which is fastened to worm wheel 41 and 40 mounted for revolution in a bearing bracket fastened to said trunk. Worm 42 is fastened on one end of the shaft of electric motor 43 engaged with worm wheel 41. Said motor is mounted on a bracket, fastened to the top 45 of said trunk, to drive pulleys 32, 32.

Idler pulleys 44, 44 are fastened to a shaft which also is mounted for revolution in bearing brackets 34, 34. Lead pulleys 45, 45 are fastened to a shaft which is mounted for revolution in bearing brackets 47, 47 fastened to front frame uprights 8, 8 to dispose said pulleys forward of door 12 with their top surface above the trunk bottom. Idler pulleys 46, 46 are fastened to a shaft which is also mounted for revolution in bearing brackets 47, 47. On pulleys 32, 32; 44, 44; 46, 46; and 45, 45 are placed belts 48, 48 the upper folds of which are in the bottom of the trunk near the floor and the side walls thereof while the lower parts of said belts are outside of said trunk. Notches $a12$, $a12$ in the bottom edge of door 12 permit said belts to pass therethrough when the door is closed.

Assume that doors 12 and 13 are fully 65 open. Laundry basket 49 is mounted on belts

48 in front of door 12. Said belts driven by motor 43 carry basket 49 through open door 12 into the trunk and said basket occupies its dotted position at 49'. In the same way baskets 51, 52, 53 and 54 were carried within the chamber of said trunk to their illustrated locations. Basket 55 has passed through the chamber and is shown in the unloading position on bars 105, 105. Basket 56 is shown on ramp $a8$ beneath the lower part of belts 48. 70 Basket 57 is shown in place on elevator platform 74. Driver sprocket wheels 58, 58 are each fastened to a short shaft 59 each of which is mounted for rotation in a bearing fastened to the side wall of one of recesses 75 10 near the rear end of the trunk. On the outer end of each of shafts 59 is fastened bevel gear 60 engaged with bevel gear $a60$ fastened on the lower end of one of diagonal shafts 61 which is mounted for revolution in bearings fastened to said trunk. On the upper end of each of shafts 61 is fastened bevel gear 62 engaged with one of bevel gears 65 which are fastened on the ends of shaft 64. Shaft 64 is mounted for revolution in 80 bearings fastened on top of said trunk disposed across the same. Spur gear 63 is fastened on said shaft 64 engaged with spur pinion 68 fastened on one end of short shaft 67 which is mounted for revolution in a bearing 85 bracket fastened on the top of the trunk. Also on shaft 67 is fastened worm wheel 66 engaged with worm 69 fastened on the other end of the shaft of said electric motor 43. Worm wheel 66 is relatively of large diameter with a large number of teeth, spur pinion 68 has relatively few teeth, spur gear 63 has relatively a large number of teeth and bevel gears 65, 62, 36 and 38 are preferably of the same diameter so that shaft 59 and 90 sprockets 58 thereon revolve very slowly relatively to motor 43. Idler sprockets 70, one of which is shown in Fig. 3, are fastened on short shafts $a70$, $a70$, see Figs. 1 and 3, and mounted for revolution in bearings fastened 95 to the side walls of recesses 10, 10, one of which is shown at $b70$ in Fig. 1, in chain relation with sprockets 58, 58, and on each pair of sprockets 58, 70 is placed one of hold-back chains 71 engaged therewith. The folds 100 of chains 71, 71 are disposed longitudinally in recesses 10, 10, and the upper part of each of said chains is supported by bar 72 fastened to the side wall of each of recesses 10. At spaced distances on chains 71 are fastened 105 hold-back lugs 73 projecting outward therefrom.

Elevator platform 74 is between pairs of guide posts 22, 22 and 23, 23 in front of the front end of the drier, and when in its full-line 115 position is at the forward end of ramp tracks $a8$, $a8$ and flush with the upper surface of the horizontally extended flanges thereof. In the front and rear side edges of platform 74 are pins 75, 75 to the rear of and adjacent guide 120

posts 22, 22 to prevent forward movements of said platform. Forward of said posts and proximate thereto in said platform edges are the lower ends of links 77, 77 engaged on pins 76, 76 in said platform edges and these link ends stop said platform from considerable rearward movements. The upper ends of said links 77, 77 are mounted on the ends of rod 78. Pins 79, 79 are set in said edges of platform 74 forward of the center thereof and with each of them is engaged the lower end of one of links 80 the upper end of which joins the upper end of said link 77 in engagement with one end of rod 78. Pin 79 is engaged in slot 81 and while the platform is supported by links 77, 80 and 77, 80 the front end of the platform may be raised to oscillate on pins 76, 76. On the rear edge of platform 74 are two hooks 82 opening upward. When the platform moves upward to the level of the upper fold of belts 48 these hooks will engage with pins 85, 85 in lugs on bearings 47 and stop further upward movement of the rear edge of the platform while the front edge thereof may move farther upward under the pull of links 77 on pins 76.

To the center of rod 78 is fastened the lower end of rope 83 which is rove over sheave 84 mounted for revolution on a pin in a bearing 30 on frame beam 24. A basket rolling down ramp a8 will roll upon elevator platform 74 where its farther progress is arrested by stop block a74 thereon may be raised by pulling downward on the free end of ropes 83 till said 35 platform has been raised to its tilted position at 74' with hooks 82 engaged with pins 85 and said basket will then roll off on to belts 48 if the front end of said belts is unoccupied. It is assumed that basket 49 shown in full lines in 40 place on the front of belts 48 had previously passed through the positions indicated by basket 57 in full lines and then in its dotted position at 57' whence it may roll onto said belts.

Short shaft 86 is mounted for oscillation in a bearing fastened to the upper front side wall of the trunk and to the external end of said shaft is fastened hammer handle 89 to the upper end of which is fastened bell hammer 90. The other end of shaft 86 extends within the drying chamber and to it is fastened arm 87 on the free end of which is mounted small wheel 88 for revolution. When wheel 88 falls downward to its dotted position at 88' hammer 90 moves to 90' and strikes bell 91.

Short shaft 92 is mounted for oscillation in a bearing fastened to the upper part of the front wall of the trunk near its front end and has crank 95 fastened thereto on its outer end. 60 To the other end of said crank is pivoted connecting rod 96 the upper end of which is pivoted to crank 97 fastened to one end of short shaft 98 on which is fastened front door dog 20. To the inner end of shaft 92 within the 65 drier is fastened arm 93 and on the outer end

of this arm is mounted small wheel 94 for revolution. Wheel 94 is shown in full lines in its lower position which causes dog 30 to occupy its full-line position where it is engageable by door catch 27. But as wheel 94 is moved upward to its dotted position at 94' dog 30 is forced backward to its dotted position at 30' out of engagement with said door catch. 70

Centrifugal exhauster 99 is installed on top of the trunk at its rear end and is driven by 75 electric motor a99. The inlet pipe 100 of this exhauster connects with a long opening across the top wall of the trunk adjacent the rear door 13, and when said door is closed draws air rearward through the length of the trunk 80 from the front end thereof.

Element housing 101 is open at its rear end and connects with a long opening 102 across the top wall of the trunk adjacent front door casing 11. Within housing 101 are mounted 85 electrical heating elements some of which are indicated at 103. When the three trunk doors are closed and exhauster 99 is operating air is drawn through heating elements 103 and through the entire length of the trunk and 90 discharged from the exhauster outlet which in practice is connected with a pipe leading without the building. Then if the elements are hot the air in passing thereamong will become heated and have the ability to take up the 95 moisture from such damp articles as may be in said trunk through which it must pass. An electric air heater is shown because its disclosure is simple. In practice I prefer to use steam coils in place thereof. 101

As stated, when the baskets pass through rear door 13 they roll over trap door 18 depressing the same to its dotted position at 18' and before each of said baskets leaves the trap door its gudgeons bear upon ramp rails 104, 104, which are fastened to the upper ends of frame uprights b8, and the basket passes downward rolling on said rails till platform rails 105, 105 are reached at the bottom of said ramp. On the rear end of rails 105 are stops 107 which arrest the farther rearward movement of the basket gudgeons which enter grooves or notches 108 in said rails forward of said stops. Here the basket comes to rest at an elevation above ramps a8, a8 beneath and the basket is free to be revolved on said gudgeons in the notches. Passage ways 106 for the basket gudgeons are provided between the adjacent ends of rails 104 and 105 and, when desired, a basket resting on rails 105 may be pushed forward out of notches 108 and the gudgeons thereon will have no supports after passing through openings 106 when the basket will drop to bear on ramps a8 and be free to roll 115 forward down the same. 106

The laundry baskets used in my drier are all alike and one of them, 49, is shown on a larger scale in Figs. 5 and 6. In shape the baskets are hollow cylinders with closed ends 120

109, 109 centrally onto each of which is fastened a gudgeon *a49*. Bands 110, 110 are fastened to each end and extend toward each other forming parts of the body adapted to bear on canvas belts 48, 48. The intervening part of the basket is preferably made of wire screen and has an opening for the admission and removal of wash. This opening is closable by hinged door 113 which may be fastened by latch 114. A transverse central partition 111 divides the basket in equal parts, and longitudinal ribs or baffles 112 are fastened to the interior of the basket body.

In operation: Assume that all parts are in their illustrated full-line positions, that motors 43 and 499 are running and that heating elements 103 are supplied with electricity, then hold-back chain belts 71, 71 are moving very slowly in the direction indicated by the arrow in Fig. 3 and canvas belts 48 are moving much more rapidly in the same direction. Basket 49 occupied by wash just removed from the centrifugal driers is being moved toward closed door 12 by belts 48 and an operative pulls down on the free end of rope 28 till door 12 is fully open and catch 27 thereof is engaged with dog 30 which retains said door in its open position. Basket 49 passes within the trunk on said belts. While door 12 was being opened door 13 was also opened allowing basket 54 to roll on trap door 18 depressing the same, against the reaction of spring 20, to its dotted position, against stop 21, at 18' and said basket passes through its dotted position at 54'. As basket 49 moves toward its dotted position at 49' the upper part of one end of the body thereof contacts with wheel 94 and when said basket reaches said dotted position this wheel has been forced upward to its dotted position at 94' forcing dog 30 from engagement with catch 27 and allowing doors 12 and 13 to close. Meanwhile operatives have removed the dried wash from basket 55 and sent it forward on ramp *a8* providing room on bars 105 for approaching basket 54. When basket 54 passes beyond the end of trap door 18 it is returned to its full-line position by spring 20 thus closing the floor opening in the trunk and completing the closure of the chamber.

When basket 49 entered the chamber the front end of the belts 48 became free for another basket and the operative at the front end of the drier raises platform 74 by pulling downward on the free end of rope 83 and said basket 57 is carried to its dotted position at 57' in a way already explained. From this position it easily rolls to the place on belts 48 previously occupied by basket 49 and moves toward closed door 12. As soon as basket 57 is off of the elevator platform the latter is allowed to return to its lower position.

In Fig. 3 empty basket 56 is shown on ramp *a8* beneath the lower folds of belts 48. By construction belts 48 have their lower

folds disposed to bear on the top of the baskets as they roll downward on ramp *a8*. The presence of these belts on the baskets prevent the latter from moving down the ramp at an accelerated rate and compel them to roll down under the control of said belts. In this manner basket 56 has passed over the ramp and onto platform 74 where it occupies the place vacated by basket 57 as described. While on the elevator platform the operative places in the basket another wash fresh from the centrifugal driers and this basket is in line to be elevated to occupy the position on belts 48 as previously described.

Exhauster 99 is continuously operating and, while the trunk doors are closed air is continuously drawn into heater housing 101 and between the hot elements therein and is heated thereby. This air passes through trunk opening 102 passes rearward through the trunk around and through the revolving baskets and amid the contents thereof, carrying away moisture therefrom, and escapes through the exhauster outlet.

Basket 49 is carried on belts 48 at their rate of movement through open door 12 till its gudgeons *a49* contact with the rear side of one of chain lugs 73, which moves very slowly through the trunk, then said gudgeons move through the trunk at the same slow rate as the chain while the basket periphery on the belts 48 continues to move with said belts resulting in the rotation of the basket on said gudgeons with a peripheral rate equal to the rate of said belt movement as the entire basket slowly advances through the heating chamber at the rate of said chain. This relatively more rapid rotation in the hot chamber of the baskets moving slowly through the same causes the contents of the baskets to cascade from the basket baffles as they move upward in rotation and allows the hot air moving through the chamber to have access to the folds of said contents and promotes the rapid drying thereof. Expressed in another way: Chains 71 do not convey the baskets through the drying chamber, neither do lugs 73 thereon engage with gudgeons *a49* on the baskets but rather they serve as stops for the gudgeons. Belts 48 convey the baskets through the chamber by contact with the peripheries thereof. The baskets are free to roll off or on the belts when not otherwise prevented. Because chains 71 move slower than belts 48 gudgeons *a49* are caused to bear against the rear edges of the chain lugs 73 and thus the baskets are caused by the belts to revolve in a backward direction while the said belts carry them forward through the chamber at the same rate as said chains travel therethrough. The drying chamber shown has a capacity for five baskets which are caused to enter and leave the drying chamber consecutively one at a

115
120
125
130
135

time and all are subjected to the drying means simultaneously. This arrangement promotes quantity drying with few operatives who are continuously employed in attending on the drying operations.

5. As stated, one of the baskets in its course through the trunk having reached the location therein indicated by 50 has raised wheel 88 and caused bell hammer 90 to be removed from close proximity to bell 91. Then, as said basket moves on, wheel 88 is allowed to drop causing said hammer to fall and strike the ball which serves as warning to the operative in front of the drier that there is room in the front end thereof for another basket and he raises the door to allow that basket which is on the front end of the belts to pass within after which the door is closed automatically when said basket is fully within the drying chamber. Simultaneously with the stroke of bell 91 a basket has reached the rear end of belts 48 and may, by construction, be pressing downward on trap door 18 and outward on door 13 forcing an opening in the rear end of the trunk and partly or fully providing air for the exhauster thus reducing the pressure at the entrance of the heater housing and allowing the air within the heating chamber to come to rest. This is a desirable condition just prior to the opening of the front door because then little cold air will enter the hot chamber while the front door is open for a brief time to place a basket in the drier. Apparently on the contrary, the illustrated construction provides for the opening of the front door to begin before the commencement of the opening of door 13 in that the point of fastening of rope 31 to rope 28 is below sheave 25 which permits some upward movement of closed door 12 before rope 31 begins to pull on door 13. But, of course, by the simple change of construction of shortening arm 15 and fastening rope 31 to rope 28 at a point on top of sheave 25 when both doors are closed, the opening of said doors by a downward pull on rope 28 will be simultaneous.

It may easily be understood that if the rear end of the trunk is desired to be the hottest it may be attained by placing the exhauster on the front end of the trunk and the heating elements on the rear end thereof, then it would be desirable to begin opening door 12 prior to that of doors 13 and 18 and the illustrated means of attaining this would be convenient.

Having thus disclosed my invention, what I claim as new therein and desire to secure by Letters Patent is:—

1. In a laundry drier, a drying chamber having capacity to contain several laundry baskets, a plurality of foraminous cylindrical laundry baskets disposed side by side in said chamber with the axes of said baskets transverse of said chamber, a gudgeon fastened to each end of each of said baskets protrud-

ing therefrom in the axis thereof, means applied to said gudgeons to retard their movement through said chamber, means applied to the peripheries of said baskets to cause said peripheries to move faster than said gudgeons in said chamber, and means to cause heated air to pass through said chamber and among and through said baskets. 70

2. A laundry drying chamber having capacity to contain several laundry baskets and having front and rear openings, a front door mounted for covering and uncovering said front chamber opening, an upper rear door mounted for covering and uncovering the upper part of said rear chamber opening, a lower rear door mounted for covering and uncovering the lower part of said rear chamber opening, means to cause all of said doors to be fully open at the same time, means to cause said front door and said upper rear door to close automatically at the same time, and means to cause said lower rear door to close automatically. 75

3. In a laundry drier, a drying chamber, two chains having lugs thereon mounted longitudinally in said chamber on opposite side walls thereof, a belt having its upper fold disposed longitudinally on the floor of said chamber, means to drive said chains and said belt in the same direction and said belt at a greater relative rate, and a plurality of hollow cylindrical, foraminous laundry baskets having axial gudgeons on the ends thereof mounted in said chamber with said gudgeons of each basket bearing against the rear edge of opposite of said lugs and the peripheral walls of said baskets bearing and rolling on and with said belt. 90

4. A laundry drier chamber adapted for the passage of laundry baskets therethrough having front and rear openings, a vertically-slidable front door adapted to close said front opening, a rear door horizontally hinged at the top thereof adapted to close said rear opening, mechanical connection between said doors adapted to fully open the same at the same time manually, a catch on said front door, a dog engageable with said front door catch, a pivoted arm mounted for oscillation in the top of said chamber disposed to bear on and be raised by said baskets passing through said chamber, and mechanical connections between said arm and said dog adapted to disengage said dog from said catch when said arm is raised. 105

5. A laundry drier chamber adapted for the passage of laundry baskets therethrough having front and rear openings, a vertically-slidable front door adapted to close said front opening, an upper rear door horizontally hinged on its upper edge to close the upper part of said rear opening, a lower rear door horizontally hinged on its front edge to close the lower part of said rear opening, a spring mounted on said lower rear door to react and 110

close the same, and means to close said front door and said upper rear door simultaneously controlled by the said passage of said laundry baskets through said chamber.

5 6. A laundry drying chamber, a shaft transverse to said chamber in front of and below the same, a shaft below the rear end of said chamber parallel with said front shaft, means to mount said shafts for revolution, 70
10 pulleys fastened to said shafts disposed with their top surfaces above and proximate the level of the floor of said chamber, belts on said pulleys with their upper folds disposed to pass from an extension in front of said 75
15 chamber rearward along the floor thereof within said chamber, an elevator platform adapted to receive and discharge a laundry baskets in front of said front shaft, means to raise said platform from below said shaft to 80
20 above the same in a tilted position disposed to discharge a laundry basket thereon on to said front extension of said belts, and means to drive one of said shafts.

7. A laundry drying chamber having front 25 and rear openings, a door to close said front opening, an upper rear door hinged at its top to close the upper part of said rear opening, a lower rear door hinged on its front edge in the plane of the floor of said chamber 30 disposed to oscillate between the bottom of said upper rear door when closed and a stop below the same, a spring mounted on said bottom-door hinge to react between said chamber wall and said door to close the same, 35 a shaft mounted for revolution below and in front of the front end of said chamber, a rear shaft mounted for revolution parallel with said front shaft in front of and below the said bottom-door hinge, pulleys fastened to 40 said shafts having their tops above and proximate the level of said chamber floor, belts on said pulleys having their upper folds disposed within said chamber along the floor thereof, cylindrical laundry baskets adapted 45 for passage through said chamber on said belts having gudgeons on the ends thereof said baskets adapted to travel through said chamber on said belts from the front end thereof and bear on top of said bottom rear 50 door thereby depressing the same to bear on said stop against the action of said spring, bars fastened to the rear of and below said chamber disposed to provide tracks for said basket gudgeons after said baskets pass from 55 said depressed bottom door, track from below said bars to an elevator platform in front of said chamber disposed to provide a rollway for said cylindrical laundry baskets beneath the lower folds of said belts, means to cause 60 said lower belt folds to bear on top of said laundry baskets on said rollway, and means to revolve one of said pulley shafts.

8. In a laundry drier, a drying chamber 65 having door openings at each end thereof and air-admission and air-discharge openings

near the ends thereof, doors to close said door openings, a heating-element housing over said air-admission opening, heating elements within said housing, means to maintain artificial temperatures in said heating elements, 70 an air exhauster, a conduit connection from the intake of said exhauster to said air-discharge opening, means to operate said exhauster, a belt operable longitudinally in said chamber over the floor thereof, several cylindrical foraminous laundry baskets adapted to pass through said chamber simultaneously rotatable by said belt and conveyable through said chamber thereon, means to operate said belt, and means to reduce the advance movement of said baskets through said chamber on said belt to a continuous movement therethrough slower than the movement of said belt.

9. In a laundry drier, the combination of a drying chamber having capacity to contain several cylindrical laundry baskets side by side therein, means to carry said baskets simultaneously forward through said chamber, and means to retard said forward movement of said baskets through said chamber whereby they are caused to revolve in said chamber.

10. In a laundry drier in combination, a drying chamber having capacity to contain several cylindrical foraminous laundry baskets disposed therein with their axes transverse thereof, means to carry said baskets forward simultaneously through said chamber, means to simultaneously retard said forward movement of said baskets through said chamber whereby they are caused to revolve on their axes as they move forward therethrough, and means to cause a current of heated air to pass through said chamber and through said baskets and among any contents therein.

11. In a laundry drier in combination, a drying chamber having capacity to contain several cylindrical foraminous laundry baskets disposed therein side by side with their axes transverse of said chamber, means to carry said baskets forward simultaneously through said chamber, means simultaneously to retard said forward movement of said baskets through said chamber whereby they are caused to revolve on their axes as they move forward therethrough, means to cause a current of heated air to pass through said chamber and through said baskets while therein and among any contents thereof, and means to cause said laundry baskets to be moved from the discharge end of said chamber to the receiving end thereof at a more rapid rate than they pass therethrough.

12. In a laundry drier, in combination, a drying chamber having receiving and discharge openings in the opposite ends thereof, means to uncover and cover said openings, endless belts having their upper folds dis-

posed on the floor of said drying chamber longitudinally thereof, means to mount said belts for longitudinal movement through said chamber, means to drive said belts, a plurality of cylindrical foraminous laundry baskets adapted for mounting on said upper folds of said belts with their peripheries bearing thereon disposed side to side in said chamber with their axes transverse thereof,
5 10 an axial gudgeon fastened on each end of each of said baskets protruding therefrom, two endless hold-back chains the upper folds of which are disposed within said chamber parallel with said belts therein adjacent and beneath said gudgeons therein, means to mount
15 said chains for longitudinal movement through said chamber, means to drive said chains in the same direction as said belts but at a slower rate, lugs on said chains protruding upward from said upper folds thereof adapted to intercept and retard the movement of said basket gudgeons through said chamber, and means to cause a current of hot air to
20 flow through said chamber and said baskets
25 therein and about any contents of said baskets.
